APPARATUS FOR ANNEALING ANNUAL COILS OF SHEET METAL

Carroll Cone, near Toledo, Ohio, assignor to Surface Combustion Corporation, Toledo, Ohio, a corporation of Ohio

Application April 13, 1948, Serial No. 20,785

3 Claims. (Cl. 263—40)

1

The present invention relates to a bell type furnace and a method of operation for annealing annular coils of sheet metal in a protective atmosphere maintained about the charge or stack of coils by a bell-type metal cover disposed thereover. In a furnace of this type the heat for the annealing operation is applied to the external side of the cover. Hence the heat is applied to the coils solely by radiation from the cover except for such heat as may be transferred from the cover to other parts of the coils by circulation of the gaseous medium (the protective atmosphere) within the cover. Conversely, cooling of the coils is effected by dissipation of heat through the walls of said cover. The object of the present invention is to provide for the circulation of said gaseous medium in such a way to provide for the heating and cooling of said gaseous medium in such a way that the heat transferred by convection should represent a substantial portion of the total heat required to be applied to coils during the annealing operation.

For a consideration of what I consider to be novel and my invention, attention is directed to the following specification and the claims appended thereto.

In the accompanying drawing forming part of this specification:

Fig. 1 is a vertical section of an annealing furnace embodying the present invention.

Fig. 2 is an enlarged fragmentary horizontal section on line 2—2 of Fig. 1.

Fig. 3 is a plan view with a portion broken away of a channeled spacer element adapted to be positioned between the annular coils to provide gas passages therebetween.

Fig. 4 is a fragmentary end view of Fig. 3.

The furnace comprises a stand 10 on which a plurality of annular coils 11 of sheet metal may be supported one above the other with their cores in vertical alignment whereby the charge is in the form of a stack having a central gas passage. During the heating and cooling operations the coils are protected against oxidation by a protective atmosphere in a bell-type metal cover 12 adapted to be disposed over the charge to form with the furnace base 13 on which the coil stand is supported a substantially gas-tight heat-treating chamber. The seating portion of the inner cover 12 preferably comprises a reinforcing band 19 of angle cross-section, having a horizontal portion welded gas tight to the side-wall and a vertical portion depending therefrom about which loose sand is disposed to reduce gas leakage from said chamber to a minimum.

2

The coil stand 10 comprises a top plate 14 having a central aperture and a lower plate 15 separated from the top plate by a plurality of radially extending spacer ribs 16 to provide a plurality of radially extending gas passages between said plates. The lower plate rests on a refractory pedestal which constitutes part of the furnace base. A radial flow fan 17 is mounted between the plates 14 and 15 coaxial with the aperture in the upper plate; hence the direction of flow of protective atmosphere is downwardly towards the fan and thence radially therefrom. The fan is driven by an electric motor 18 appropriately secured to the underside of the furnace base.

Heat for the annealing operation is provided by a portable heating hood 20 disposed over the metal cover 12. On completion of the heating operation, the heating hood is removed but the protective cover 12 is left in place; hence cooling of the coils is by dissipation of heat through the walls of said cover. The heat producing means in the hood 20 is of secondary importance but will ordinarily consist of heat radiating elements 21 such as internally fired tubes.

The furnace thus far described involves nothing new and is typical of a conventional bell-type annealing furnace.

In the present invention, the adjacent ends 30 of the coils are separated from each other by an annular metal separator 22; hence any heating or cooling of the separator will result in similar heating or cooling of the ends of the coils in contact therewith. Each separator 35 comprises a plurality of open-ended gas passages 23 between the inner and outer rims thereof so that gaseous medium is free to flow through said passages. In the present invention the internal heat transfer area of the coil separators is from 1.5 to 2.0 times the net area of the adjacent coil ends, this increased area being provided by the combined area of the side walls 24 of said passages, it being understood that the height and number of said walls are the determining factors.

The fan 17 is sufficiently powerful to produce sufficient partial vacuum in the core of the stack of coils to cause the gaseous medium about the stack to flow through separator passages 23 with a velocity between 2000 and 3000 feet per minute. A closure plate 25 on top of the stack restricts the flow of gaseous medium through and around the stack to the desired minimum.

As best shown in Fig. 2, the side wall of the protective cover 12 is corrugated to provide a contact area for the gaseous medium inside of the cover that is between 1.75 and 2.25 times

the projected area of said wall thereby permitting a correspondingly greater amount of heat to be exchanged between said wall and said atmosphere. The furrows and ridges of said corrugations are vertical. The use of a reinforcing band 19 of angle cross-section makes the vertically corrugated cover substantially rigid by preventing the corrugations from spreading accordion-fashion, and also provides a depending blade-type seal.

From the foregoing explanation it will be appreciated that there are two distinct heat transfer processes involved in heating or cooling the coil charge. Radiation heat transfer, on the one hand, occurs primarily between the inner surface of the protective cover and the outer wraps of the coils, in quantity which varies directly with the projected inner surface of the cover, and at a rate which increases rapidly with temperature. The rate of heating by radiation heat transfer is severely limited by the rate of heat transfer from the outer wraps of the coils to the center thereof. Convection heat transfer, on the other hand, delivers heat energy primarily to or from the coil ends in contact with the work separators used in the preferred arrangement. The quantity of heat transferred by convection varies with the developed rather than the projected area of the inside cover surface, the effective surface or heat transfer area of the coil separators, and the power and efficiency of the circulating fan.

Since convection heat transfer depends upon wiping heat off of the inner cover and delivering it to the coils as by a separator, a proper design of the inner cover together with a correspondingly careful choice of a coil separator and a circulating fan will be required to obtain maximum benefits from each.

Because of the basic differences in the two heating effects, the results secured in temperature uniformity, heating and cooling time requirements and the shape of the time-temperature curve secured during heating and cooling may be drastically modified by changing the relative amounts of heat transferred by radiation and convection. In general, the change to more heating by convection increases overall heat transfer effects since radiation heating is not necessarily reduced by the expedients used to promote convection heat transfer. However, such expedients represent additional items of investment and operating cost, to the extent that the determination of the most economical distribution of the heat transfer burden between these two processes becomes a very important step in the design of coil heating equipment; hence as already stated, I have found it desirable to design the equipment to satisfy the following empirical relations:

1. The internal heat transfer area of coil separators should total between 1.5 and 2.0 times the net area of adjacent coil ends.
2. The velocity of gas circulation through the open passages through such coil separators should be between 2000 and 3000 feet per minute.
3. The developed inside surface area of the protective cover should be between 1.75 and 2.25 times the projected area of that surface.

I believe that with the combination of heating effects as described, and used in accordance with the preferred ratios defined above, I obtain the most economical operation with the best metallurgical results.

What I claim is:

1. Apparatus for annealing a stack of coils of sheet metal in a protective atmosphere comprising, in combination, a base for supporting said stack of coils, separators for spacing the coils in said stack, said separators being provided with passages for flow of said protective atmosphere between the interior and the exterior of said stack, a gas-tight cover for said stack having 10 a single vertically corrugated cylindrical side wall closely surrounding said stack, means comprising a power-driven fan for circulating said protective atmosphere at high velocity along the channels formed by said corrugations and 15 through the interior of said stack, said atmosphere also flowing through the passages in said separators, and means for applying heat directly to the exterior of the corrugations forming the channels along which said atmosphere is circulated, said corrugated cylindrical side wall providing transfer of heat to said coils by conduction at a substantially greater rate than a smooth cylindrical side wall, and providing transfer of heat to said coils by radiation at substantially as great a rate as a smooth cylindrical side wall.
2. Apparatus according to claim 1, comprising a supporting ring having a horizontal flange secured to the foot of the corrugated cylindrical 20 side wall of the cover, and having a depending cylindrical portion serving as a blade for engagement with the base to confine the protective atmosphere within the cover.
3. In a protective atmosphere annealing furnace comprising heating means, a base supporting a stack of coils of sheet metal; separators between said coils that provide passages between the interior and the exterior of said stack, and a high-capacity power-driven fan for circulating 25 the protective atmosphere through the interior of said stack and through the passages in said separators, the combination therewith of a gas-tight cover, interposed between said heating means and said stack of coils, having a single vertically corrugated cylindrical side wall closely 30 surrounding said stack, whereby said protective atmosphere flows at high velocity along the channels formed by said corrugations, said corrugated cylindrical side wall providing transfer of the furnace heat to said coils by conduction at a substantially greater rate than a smooth cylindrical side wall, and providing transfer of the furnace heat to said coils by radiation at substantially as great a rate as a smooth cylindrical side wall.
